CLAIM

The ornamental design for a solar panel awning, as shown and described.

DESCRIPTION

FIG. 1 is a top, front, and left side perspective view of a solar panel awning showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a top, front and left side perspective view of the solar panel awning in an exemplary embodiment of use; and, FIG. 9 is a top, front and left side perspective view of a plurality of solar panel awnings in an exemplary embodiment of use.

The broken lines in the figures represent portions of the solar panel awning and use environment that form no part of the claimed design.

1 Claim, 9 Drawing Sheets
